COUNTER CABINET

Gabriel D. Weiss and Morris Friedman, Philadelphia, Pa., assignors to Nancy Lynn, Inc., East Greenville, Pa., a corporation of Pennsylvania

Application May 24, 1952, Serial No. 19,867

Term of patent 3½ years

(CL. D80—11)

To all whom it may concern:

Be it known that we, Gabriel D. Weiss and Morris Friedman, both citizens of the United States, both residing at Philadelphia, county of Philadelphia, State of Pennsylvania, have invented a new, original, and ornamental Design for a Counter Cabinet, of which the following is a specification, reference being had to the accompanying drawings, forming a part thereof, wherein:

The dominant features of the design reside in the portions shown in full lines.

We claim:

The ornamental design for a counter cabinet, as shown and described.
